(57) **CLAIM**

The ornamental design for a folding display notebook computer, as shown and described.

DESCRIPTION

FIG. 1 is a front perspective view of the folding display notebook computer wherein the display panels are opened

flat and supported on a stand, the stand not being part of the claimed design;

FIG. 2 is a rear perspective view thereof;

FIG. 3 is a front perspective view thereof;

FIG. 4 is a rear perspective view thereof;

FIG. 5 is a front view thereof;

FIG. 6 is a back view thereof;

FIG. 7 is a top view thereof;

FIG. 8 is a bottom view thereof;

FIG. 9 is a left side view thereof;

FIG. 10 is a right side view thereof;

FIG. 11 is a front perspective view thereof shown in a laptop orientation;

FIG. 12 is a rear perspective view thereof;

FIG. 13 is a front view thereof;

FIG. 14 is a back view thereof;

FIG. 15 is a top view thereof;

FIG. 16 is a bottom view thereof;

FIG. 17 is a left side view thereof;

FIG. 18 is a right side view thereof;

FIG. 19 is a perspective view thereof in a tent-like orientation;

FIG. 20 is another perspective view thereof;

FIG. 21 is a front view thereof;

FIG. 22 is a back view thereof;

FIG. 23 is a top view thereof;

FIG. 24 is a bottom view thereof;

FIG. 25 is a left side view thereof;

FIG. 26 is a right side view thereof;

FIG. 27 is a perspective view thereof;

FIG. 28 is another perspective view thereof;

FIG. 29 is a front view thereof;

FIG. 30 is a back view thereof;

FIG. 31 is a top view thereof;

FIG. 32 is a bottom view thereof;

FIG. 33 is a left side view thereof; and,

FIG. 34 is a right side view thereof.

(Continued)

Broken lines in the drawings are included for the purpose of illustrating an environment only and form no part of the claimed design.
